UNITED STATES PATENT OFFICE

FREDERICK H. HOUSE, OF BUFFALO, NEW YORK, ASSIGNOR TO JACOB HOUSE & SONS,
OF BUFFALO, NEW YORK, A PARTNERSHIP

DESIGN FOR A STATUETTE OR SIMILAR ARTICLE

Application filed January 14, 1932. Serial No. 42,475. Term of patent 7 years.

To all whom it may concern:

Be it known that I, FREDERICK H. HOUSE, a citizen of the United States, residing at Buffalo, Erie County, State of New York, have invented a new, original, and ornamental Design for a Statuette or Similar Article, of which the following is a specification, reference being had to the accompanying drawings, forming a part thereof.

In said drawings:

Fig. 1 is a front view of a statuette embodying my design.

Fig. 2 is a side view thereof.

Fig. 3 is a rear view thereof.

I claim:

The ornamental design for a statuette or similar article, substantially as shown.

FREDERICK H. HOUSE.
